UNITED STATES PATENT OFFICE

LUTHER M. ROBINSON, OF BLACKWELL, OKLAHOMA

APPARATUS FOR RAISING FLUIDS FROM OIL WELLS

Application filed June 13, 1927. Serial No. 193,380.

This invention relates to an apparatus for raising fluids from oil wells.

As is well known, fluid is raised from an oil well by the working barrel of a pump. The amount of fluid raised for each stroke is limited by the relatively small capacity of the working barrel, due to the relatively small diameter of the tubing in the well.

My invention contemplates an apparatus for increasing the capacity of the pumping apparatus, by increasing the oil lift due to a plurality of pistons operated by a single plunger and a plurality of working barrels, one for each piston. The reciprocating pump has two stages, the first operating in the usual way having a diameter equal to the pump plunger and the second of greater capacity, and as both pistons operate at the same time, it is obvious that more than the usual amount of oil will be raised at each lifting stroke of the plunger.

An important feature of my invention is that it serves as a combined gas and liquid pump and as illustrated, the larger and upper working barrel acts as a gas relief device, the piston in the upper working barrel pumping off the gas, where any exists, so that the smaller and lower working barrel will pump off the liquid or "fluid" as it is generally called.

The novelty of my invention will be better understood by reference to the following description in connection with the accompanying drawings in which:

Fig. 1 is a sectional view through a pump mechanism constructed in accordance with my invention.

Fig. 2 is an enlarged perspective view of one plunger, one piston, the outer and upper working barrel and the casing.

Fig. 3 is an enlarged fragmentary sectional view through the pump mechanism of both barrels.

Fig. 4 is a sectional view on the line 4—4 of Fig. 1 and

Fig. 5 is a sectional view on the line 5—5 of Figure 1.

Referring, now, to the drawings by numerals of reference, 1 designates a string of pipe in which is a seating collar 2. The seating

collar has a conical seat 3 carrying a casting in the form of a seating nut 4 in which are passage ways 5. The seating nut carries a strainer 6. The seating nut, also, supports the working barrels 7 and 8 in spaced parallel relation. At the bottom of the working barrel, with the effective part of the outer barrel above the inner one, is a standing valve 9 which may be of any preferred construction. The hollow plunger 10 carries a traveling valve 11 of usual construction and it carries the usual piston 12 with the usual cups 13. At the top of the hollow plunger is a sand valve 14. Therefore, when the plunger moves on its up-stroke, its end 15 will raise, unseating the standing valve 9, drawing oil into the working barrel. On the down-stroke, the standing valve 9 will close and the valves 11 and 14 will unseat, discharging oil into the pipe 1. This, in effect, would be usual practice. In addition to the working barrel 7 I have provided a working barrel 8 which is connected to the seating nut 4 and surrounds the passage ways 5 and which surrounds the working barrel 7. Since the effective part of the barrel 8 is above the barrel 7, I have provided a lower working barrel and an upper working barrel. Obviously, the distance the upper working barrel is above the lower one will depend to some extent upon the estimated gas pressure encountered in the well. Therefore, these distances may be varied to suit the particular conditions of the particular well in which the device is to be installed.

At the top of the working barrel 7 is a valved head 16 having passage ways 17 leading from the space between the two working barrels 7 and 8 to the stage 18 above the head and within the working barrel 8. The passage ways 17 are normally closed by standing valves 19 corresponding to the standing valve 9. In the stage 18 is a piston 20 carried by the plunger 10 and it has passage ways 21 with working valves 22 normally closing them. At the head or upper end of the upper working barrel 8 is a head 23 with passage ways 24 normally closed by the sand valves 25. Consequently, when the plunger 10 moves on its up-stroke, oil will be pulled through the passage ways 5 into the space between the

working barrels 7 and 8 and into the stage or space 18, because the standing valves 19 will be unseated. Therefore, the standing valves 9 and 19 will be unseated at the same time or during the same up-stroke of the plunger 10. On the down-stroke of the plunger 10, the standing valves 9 and 19 will be closed. The traveling valves 22 and the sand valves 25 will unseat so that oil will pass from the working barrel 8 into the pipe 1. The pipe may be of relative large tubing or it may be the casing in the well. The valves 19, 22 and 25 may be arranged in circular series about the axis of the plunger, each valve closing a port or passage way. The combined areas of the passage ways providing ample spaces through which the oil may pass and by reference to the drawings it will be apparent that the fluid from both working barrels will discharge into the pipe 1 where it may flow to the top of the well.

With such a construction, the output of the well will be materially increased over what is possible with a single stage, single acting pump. My invention, constructed as shown, really consists of a multiple stage, single acting pump structure with a plurality of pistons operated by the same plunger, one piston being of greater diameter than the other, with the several pistons arranged in tandem. I do not wish to be limited, however, to the exact details of construction shown, for obviously, changes in form, proportion and minor details of construction may be made without departing from the spirit of my invention or sacrificing any of its advantages.

A by no means unimportant feature of my invention is the provision of means whereby the illustrated structure serves as a combined gas and liquid pump. Gas accumulating in the well may pass into the upper and larger working barrel which serves as a gas relief device. The piston 20 will pump off the gas while the smaller piston 12, in the working barrel 7, pumps off the liquid. This occurs only where there is an excess of gas accumulation in the well. When the gas is pumped off, the larger and upper working barrel and the piston will be effective in pumping off liquid. In other words, this invention has an advantage over the ordinary pump because with the ordinary pump, using a single working barrel, the gas pressure is sometimes enough to raise or unseat the standing valve and the traveling valve and hold them open while the plunger is moving up and down. This, obviously, destroys the effectiveness of the pump. With my invention, the larger and upper working barrel will take care of the gas because the lighter valves 19 will unseat before the heavier valve 9, consequently, the gas pressure will be relieved through the upper working barrel. In this connection, it will be noted that all the valves of the smaller

working barrel and plunger are heavier than the valves associated directly with the upper working barrel.

What I claim and desire to secure by Letters-Patent is:—

1. In combination with a string of pipe having a seating collar, a working barrel carried by the seating collar, a working barrel within the first named working barrel, independent plungers for the working barrels, a rod for simultaneously operating the said plungers within the respective working barrels, each working barrel having an independent inlet, part of the first named working barrel extending above the second mentioned working barrel and standing valves at the tops of the respective working barrels.

2. In combination with a string of pipe having a seating collar, a working barrel carried by the seating collar, a working barrel within the first named working barrel, independent plungers for the working barrels, a rod for simultaneously operating the said plungers within the respective working barrels, each working barrel having an independent inlet, part of the first named working barrel extending above the second mentioned working barrel, standing valves at the tops of the respective working barrels and standing valves in the plunger of the first named working barrel.

In testimony whereof I affix my signature.

LUTHER M. ROBINSON.
